Specification of Letters Patent.

Patented Aug. 4, 1914.

Application filed March 24, 1909. Serial No. 485,525.

To all whom it may concern:

Be it known that I, HARRIE A. BALLARD, of Boston, in the county of Suffolk and State of Massachusetts, have invented certain new and useful Improvements in Lasts, of which the following is a specification.

This invention relates to lasts and its object is to provide a last which may be more readily withdrawn from a lasted shoe than 10 lasts now commonly used.

In one respect the last forming the basis of this invention is similar to the last illustrated in my co-pending application filed March 9, 1909, Serial No. 482,390.

15 In the present invention the last comprises a heel-part and a forepart formed of two sections of which one section has sliding connection with the heel-part and of which the other section has sliding connection with its 20 complementary forepart section. The point of similarity between the present invention and that of the above-mentioned application lies in the form of connection between the forepart and heel-part.

25 The chief feature then of the present invention is the forming of the forepart in two sections as aforesaid, and in providing suitable connecting means by which they may be held in sliding relation one with the other.

30 Taken as a whole the last herein illustrated and described is adapted to be first shortened for the purpose of facilitating the withdrawal of the heel portion, and consequently the friction incumbent upon the 35 forepart by reason of its snug fit in the shoe is sufficient to detain the relatively loose section of the forepart when the other section is withdrawn. The two sections of the forepart are divided on a line which is oblique 40 to the longitudinal. Consequently when one section is moved relatively to the other by reason of the withdrawal of one and the detention of the other, the aggregate width of the two sections is materially decreased so 45 that the two sections may then be withdrawn as a whole without crowding or stretching the narrow portion of the shoe commonly called the "waist."

The means for connecting the two forepart sections provides for movement of the relatively movable section in a line which conforms approximately to the mean curvature of the forepart of the shoe or last, thus enabling the section first withdrawn to move

according to the general curvature of the toe 55 portion.

Of the accompanying drawings which illustrate one form in which the invention may be embodied, Figure 1 is a top plan view of a last of which a portion is broken 60 out. Fig. 2 is a side elevation of which a portion is broken out. Fig. 3 is a longitudinal section of the waist portion of the last including appropriate mechanism for locking the heel part with one of the forepart 65 sections. Fig. 4 is a section on line 4-4 of Fig. 2.

The same reference characters indicate the same parts wherever they occur.

The last comprises essentially a heel-part 70 10 and a forepart formed of two sections 11 and 12. The inner section or part 11 and the outer section or part 12 are formed by dividing the forepart on the line 13 which is oblique to the longitudinal line of the last, 75 and the heel-part is connected directly with the section 11 by means of sliding interlocking tongue and groove portions 14 and 15. As here shown, the tongue 14 is formed at the rear end of the section 11 and the groove 80 15 is formed in the front portion of the heel-part 10. The heel-part and forepart are divided on a plane which is inclined to a perpendicular transverse plane thus providing both faces 16 and 17 on which the 85 two parts are adapted to slide with shortening effect. The rear end of the section 12 also abuts against the heel portion when it is in closed position.

The means here shown for connecting the 90 two sections 11 and 12 comprise a plate 18 secured by screws 19 in the contiguous face of the member 11, and screws 20 extending through the slots 21 in said plate and into the section 12. The section 11 is rabbeted 95 for the reception of the plate 18 so that the exterior face of the plate may be flush with the face of the section. The section 11 is also provided with rabbeted chambers 22 for the reception of the heads of the screws 20. 100 The heads engage the inner face of the plate and thus hold the section 12 against the section 11 and at the same time permit movement of the section 12 longitudinally of the plate. By reference to Fig. 2 it will be observed that the slots 21 are curved. The curvature of the slots is such as to guide movement of the section 12 to conform to 105

the mean curvature of the forepart of the last. The two forepart sections are assembled in the following manner:—Two holes 23 and 24 are bored laterally through the 5 section 11 beginning respectively at the rear ends of the rabbeted chambers 22. The plate 18 is then attached to the section 11 and the screws 20 are inserted through holes 23 and 24 and screwed into the section 12. After 10 the insertion of the screws 20, the holes 23 and 24 are filled with plugs 25.

Suitable mechanism may be provided for locking the heel-part with the section 11. An appropriate mechanism is shown in Figs. 15 2 and 3 and is installed by first boring through both parts when they are in closed position so as to provide sockets 26 and 27. In the socket 26 is inserted a tubular holder 28 containing a plunger 29. The upper end 20 of the holder 28 is open but the lower end is partially closed by an end wall in which is an aperture for the reception of a stem 30 formed on the plunger 29. A helical spring 31 is coiled about the stem and compressed 25 between the end wall of the holder and the plunger and exerts its tension to force the plunger into the socket 27 of the heel-part. For the purpose of limiting the outward movement of the plunger the rear 30 end of the stem may be provided with a head 32 for engagement with the end wall of the holder.

The operation in removing the last from a shoe is as follows: The heel portion is first 35 moved upwardly and forwardly upon the section 11 to shorten the last so that the heel portion may be readily withdrawn. For this purpose a hooked tool may be used first for pressing the locking plunger 29 out of the socket 27 and then for drawing the heel portion by its insertion in the said socket. The heel portion may then be grasped and withdrawn bodily in a direction transverse 40 to the abutting faces of the forepart and heel-part. Such withdrawal of the heel-part necessarily causes the withdrawal of the section 11, but by reason of the width of the forepart in excess of the comparatively narrow waist of the shoe, the section 45 12 is detained in the shoe after the section 11 begins to leave. The section 11 is guided toward the rear by the curved slots 21 and when the forward ends of the slots engage the screws 20, the section 12 is moved bodily 50 with the sections 10 and 11 now partially withdrawn. At this time the aggregate

width of the forepart is so materially reduced by reason of the oblique movement of the section 11 that the forepart is enabled to pass through the waist of the shoe without stretching or distorting the same and the last is adapted to be freely withdrawn from the shoe.

Having thus explained the nature of my said invention and described a way of constructing and using the same, although without attempting to set forth all of the forms in which it may be made or all of the modes of its use, I declare that what I claim is:

1. A last comprising a heel-part, and a forepart divided in two sections of which one has sliding connection with the heel-part by which the last may be shortened, and of which the other section has sliding relation 75 with its complementary section and is movable to and from engagement with the heel-part.

2. A last comprising a heel-part and a forepart divided perpendicularly to the sole 80 into two sections both of which are adapted to abut against the heel-part, said sections being slidably connected so that one is relatively movable in a path substantially parallel to the mean longitudinal curvature of the 85 forepart of the last, and means for connecting the other section with the heel-part.

3. A last divided into a forepart and a heel-part by a transverse section oblique to the bottom of the last, and having its forepart divided into an inner part and an outer part by a longitudinal oblique section intersecting the longitudinal median plane of the last, the rear ends of the inner part and outer part of the forepart of the last being 95 flush.

4. A last comprising a forepart and a heel-part, means for slidably connecting said parts, said forepart comprising an inner portion and an outer portion having 100 their inner end faces abutting against the confronting face of the heel-part, and having confronting abutting faces oblique to the longitudinal median line of said forepart, and means for slidably connecting said 105 inner and outer portions of the forepart.

In testimony whereof I have affixed my signature, in presence of two witnesses.

HARRIE A. BALLARD.
